UNITED STATES PATENT OFFICE.

WILLIAM PRESSMAN, OF NEW YORK, N. Y.

REVERSIBLE VEST.

1,047,700.

Specification of Letters Patent. Patented Dec. 17, 1912.

Application filed April 4, 1911. Serial No. 618,780.

To all whom it may concern:

Be it known that I, WILLIAM PRESSMAN, a subject of the Czar of Russia, and a resident of the city of New York, borough of Brooklyn, in the county of Kings and State of New York, have invented a new and Improved Reversible Vest, of which the following is a full, clear, and exact description.

My invention relates to a new and novel form of reversible vest, and more particularly relates to that class of vests wherein the different faces present vests of different characters.

An object of my invention is to provide a reversible vest neat in construction and adapted to be worn to present in effect either a single-breasted vest or a double-breasted vest.

A further object of my invention is to provide a reversible vest having means for obtaining the same, whereby a bulky appearance along the fastening line will be eliminated and a smooth tailored effect will be produced.

I attain the above-outlined objects by making both the inside and the outside of the vest of a finishing material, and inserting within the meeting edges of the vest and between the layers of finishing cloth, a lining doubled upon itself to thereby afford a pocket for the insertion of the sides of a corresponding pocket on the opposite edge. Between these two overlapping edges is provided on opposite sides, the common form of button-and-buttonhole connection.

With the above and other objects in view, as will more fully hereinafter appear, the present invention consists in certain novel details of construction and arrangement of parts hereinafter fully described, illustrated in the accompanying drawings and more particularly pointed out in the claim.

Reference is to be had to the accompanying drawings, forming a part of this specification, in which similar characters of reference indicate corresponding parts in all the figures, and in which—

Figure 1 is a perspective view showing a preferred embodiment of my invention with the single-breasted effect; Fig. 2 is a detailed plan view showing the connection between the edges of the vest disclosed in Fig. 1, with the flaps open; Fig. 3 is an enlarged transverse sectional view taken on the line 3—3 of Fig. 1; Fig. 4 is a view similar to Fig. 1, but showing the vest reversed, pre-

senting a double-breasted effect, Fig. 5 is a detailed sectional view showing the linings and facing means on an enlarged scale from that shown in Fig. 3, the parts being separated to show various fasteners.

Described more in detail, Figs. 1 and 2 disclose a vest 5, one side or face of which, as shown in Fig. 1, presents a single-breasted effect, while this same vest turned inside out or reversed shows a double-breasted effect, as shown in Fig. 4. The front face of the vest is made of one style of finishing material 6 and the rear or inside face is of a different style of finishing material 7. From a point 8 within the neck of the vest and extending down the meeting edges to a point 9 adjacent the bottom, is inserted a lining 10 of any preferred material, which lining is bent back upon itself, as shown at 11, to form a flat elongated U-shaped lining for the ends of the facing materials. One of said linings 10 extends between and terminates at the edges of the side 19 and the member 13 and contains the edge of the side 17 and part of one side of the opposite lining 10. This opposite lining 10 is disposed between the sides 12 and 17, one end terminating at the edge of the side 17 and the other end fastened to the side 12 some distance adjacent its edge and has positioned therein the outer edge of the member 13 and part of the lining 10 between the side 19 and member 13.

On the double-breasted side, shown in cross section in the upper part of Figs. 3 and 5, the free outer overlapping side 12 is extended across the underlapping member 13 some material distance to give the double-breasted effect shown in Fig. 4, and is held in place by a row of buttons 14 placed adjacent the outer edge of the side 12. As is customary with this double-breasted effect, an additional parallel row of buttons 15 may be used.

On the single-breasted side, as shown in Fig. 1, a single row of buttons 16 is fastened to the side 17 when passed through buttonholes 18 on the side 19 coacts with the side 17 to form the single-breasted effect. If desired, the double-breasted vest may have a conventional form of collar 20.

Many changes could be made in the above construction and many apparently widely different embodiments of this invention could be made without departing from the scope thereof. It is intended that all mat-

ters contained herein in the above description or shown in the accompanying drawings, shall be interpreted as illustrative and not in a limiting sense.

5 Having thus described my invention, I claim as new and desire to secure by Letters Patent:

10 As a means for fastening a reversible vest having a double-breasted and a single-breasted front, a U-shaped lining connecting the edge of one side of the double-breasted front with the edge of the adjacent single-breasted front, a U-shaped lining having one edge fastened to the edge of the other side

15 of the single-breasted front and its other edge fastened to the overlapping side of the double-breasted front, each of said linings adapted to contain an edge of an opposite front and part of the opposite lining, and fasteners holding said sides in place. 20

In testimony whereof I have signed my name to this specification in the presence of two subscribing witnesses.

WILLIAM PRESSMAN.
